MATERNITY MATTRESS PAD
Royal B. Talley, Jr., 906 Phillips St., Garner, N.C.
Filed May 10, 1962, Ser. No. 193,716
1 Claim. (Cl. 5—338)

This invention is concerned with a pad that can be placed on a mattress or other sleeping surface by expectant mothers or other persons with enlarged abdomens to assist in sleeping or resting comfortably in a face-down position.

A general object of the invention is to provide a relatively small pad that can be placed on mattresses and the like and which is adapted to comfortably support an enlarged abdomen.

Another general object of the invention is to provide for persons with enlarged abdomens a sleeping pad which can be converted to other purposes.

Another more specific object of the invention is to provide for persons with enlarged abdomens a multi-section sleeping pad that can be disassembled so as to form pillows from each section.

Another object is to provide for persons with enlarged abdomens a sleeping pad that includes washable and removable covering over the entire pad including the abdomen supporting surface.

Another object is to utilize a fitted sheet as a means of both covering and retaining together pillow-like sections forming an abdomen supporting pad.

The above and other objects will appear as the description proceeds. In the drawings like numerals have been used to identify similar parts and in which:

FIGURE 1 is a perspective assembly type view showing pad sections, a fitted sheet cover and a depth adjustment plug made according to the invention.

FIGURE 2 shows the shape of fabric blank used to form the fitted sheet employed with the invention.

FIGURE 3 shows the shape of fabric blank used to form a cover for the abdominal opening.

FIGURE 4 shows the assembled pad of the invention in plan view.

FIGURE 5 shows the assembled pad of FIGURE 4 as viewed from the bottom.

FIGURE 6 is a cross-section taken along line 6—6 of FIGURE 4 and as if the adjustment plug were installed.

FIGURE 7 is a perspective assembly view of an alternative embodiment employing individual covers over each pad section.

FIGURE 8 is a plan view showing the embodiment of FIGURE 7 assembled.

FIGURE 9 is a perspective showing how the individual pad sections may be employed as pillows.

This invention in general consists of forming a pad from two symmetrical, relatively thick sections of polystyrene foam, artificial sponge rubber or similar material.

Unlike prior art practices which have taught the use of full length and difficult to clean mattresses with openings adapted to accommodate enlarged abdomens, this invention employs a relatively short, relatively thick pad of artificial sponge or similar material which can be placed on the regular mattress and which has a centrally disposed opening to receive the enlarged abdomen. The pad of the invention is formed of two symmetrical sections of the sponge material with the required opening being divided equally between the sections. Each section generally resembles a type of throw pillow frequently used by both adults and children in viewing television, reading in bed and the like and when not being used as an abdominal support, both sections may be readily put to such alternative use.

To form the pad, the sections are held together so as to

2

form a relatively flat supporting surface with a central opening. For this purpose, the invention in one embodiment employs a fitted sheet that covers both sections and holds them together in proper relationship. The sheet 5 covers the surface on which the expectant mother lies and covers the opening surface in which the abdominal portion of the body resides during rest. The fitted sheet being easy to launder makes the pad a more acceptable product from the viewpoint of cleanliness. In another embodiment, each of the sections is individually covered and they are fastened together to form the pad. By simply unfastening the covers, the pad is immediately converted to two pillows.

In the drawings, 10 and 11 represent a pair of symmetrical sections of artificial sponge material which when held together form the desired abdomen supporting pad. As will be seen from the drawings each of the sections includes a hollowed-out portion as at 12 and 13 on one edge which when placed together as indicated form an inverted, substantially frusto-conical shaped opening for receiving the abdomen. The means for retaining the two sections together so as to form the desired pad may vary. However, to get the full benefits of the invention, the means used should be simple and should allow for the individual sections to be easily separated in order that they may be quickly converted to other purposes.

One convenient means of retaining the sections is found in the use of a special fitted sheet as generally indicated at 15. The body of sheet 15 is made from suitable sheeting fabric cut generally in the shape of the body blank indicated at 16 in FIGURE 2. Blank 16 is provided with a hole 17 that coincides with the abdominal opening of the pad and to which is stitched a pair of collar shaped blanks 18 and 19 shaped as indicated at 20 in FIGURE 3 and 25 which together form a covering over the opening surfaces. As indicated by the dotted lines in FIGURE 2, the fabric side, as at 21, folds over the respective side of the pad and the fabric edge, as at 22, folds under the bottom of the pad. The sheet is stitched at each corner as at 23, 30 around the opening as at 24 and where the collar shaped panels join as at 25. Once installed over the pad sections, the fitted sheet automatically brings the sections into proper relationship and furnishes an easily washable fabric covering over all of the surfaces of the pad exposed to the user including a covering shaped to fit over the abdominal opening.

FIGURE 4 illustrates the general appearance of the pad as it appears from the top when ready for use while FIGURE 5 represents the general appearance of the pad when viewed from the bottom and with the fitted sheet in place. Since the size of the expectant mother's abdomen will change during the pre-natal period, the invention provides for use of a frusto-conical shaped plug 30 which can be inserted in the opening as indicated in FIGURE 1 and in section in FIGURE 6, to vary the depth of the opening so as to adjust to different size abdomens. Plug 30 for the sake of both comfort and appearance is preferably enclosed in a removable sheeting type fabric matching the fabric employed in the sheet.

60 An alternative arrangement for carrying out the invention is illustrated by FIGURES 7 and 8. In these figures 35 and 36 represent removable fabric covers individually fitted to the contours of the sponge rubber sections 10 and 11. Since individual pillow covers of this type are well known including the Zipper constructions commonly used for making the same removable, the covers are not otherwise shown in detail. Covers 35 and 36 are each provided with fastening buttons as generally indicated at 37 and 38 in order that the sections 10 and 11 may be held in proper abutting relationship to form the pad and abdomen opening. As seen in the top view illustrated by FIGURE

8, this effect is achieved with the covers abutted and the fasteners fastened as shown.

While it is believed that the multi-section pad concept offers the greatest advantages, it is contemplated that instead of the split type pad some may wish to employ a relatively short, solid pad not shown, in conjunction with a fitted sheet as shown having the special abdominal opening covering. This does realize the advantage of not being required to utilize a full length mattress for the purpose and also realizes the further advantage of having 10 an easily washable covering over the pad proper as well as over the abdomen opening surfaces which advantages are not found in the prior art.

As previously mentioned, one of the principal advantages of the abdomen supporting pad of the invention in its preferred embodiment is that it can be adapted to other uses by reason of the fact that each of the sections forming the pad is readily adapted to use as a pillow as illustrated by FIGURE 9. Such use can be made either from the uncovered sections 10 and 11 or from one of the 15 covered sections as illustrated by FIGURE 9. From the viewpoint of product acceptance, it can be seen in summary that the expectant mother will be much more attracted to use of the pad knowing that the pad has other uses once it has served the immediate of supporting 20 the enlarged abdomen.

Having thus described my invention, what I claim is:

A relatively thick and resilient pad for placing on a substantially larger sized mattress and having a centrally located inverted frusto-conical shaped opening providing 25

an inwardly sloping wall adapted to receive and support an enlarged abdomen, said pad being formed from two symmetrical sections having vertically divided frusto-conical shaped hollowed out portions which mate to form said opening and between which sections said opening is 5 equally disposed, said sections being substantially the size of and adaptable to use as throw pillows and the like; and sanitary cover means for removably securing said sections tightly together in substantially the same plane whereby to form said pad and said opening and to make said pad adaptable both to supporting said abdomen and furnishing said pillows, said cover means comprising a sheet having fitted corners adapted to be secured to the corners of said pad, a main sheet portion covering the top of said pad and an inverted hollow frusto-conical shaped centrally located section seamed to said main portion and adapted to preserve said opening while covering said wall.
